CLAIM

The ornamental design for a combined curling iron with cover, as shown and described.

DESCRIPTION

FIG. 1 is a top plan view of a combined curling iron with cover showing our new design;

FIG. 2 is a bottom plan view thereof;

FIG. 3 is a front elevational view, the rear elevational view being a mirror image thereof;

FIG. 4 is a left end elevational view thereof; and

FIG. 5 is a right end elevational view thereof.
